UNITED STATES PATENT OFFICE

173,115

HANDLE FOR CUTLERY OR THE LIKE

Thomas Lamb, New Canaan, Conn.

Application December 4, 1953, Serial No. 27,926

Term of patent 14 years

(Cl. D22—3)

To all whom it may concern:

Be it known that I, Thomas Lamb, a citizen of the United States, residing at New Canaan, in the county of Fairfield and State of Connecticut, have invented a new, original, and ornamental Design for a Handle for Cutlery or the like, of which the following is a specification, reference being had to the accompanying drawing, forming part thereof.

Figure 1 is a top plan view of a handle for cutlery or the like embodying my new design.

Figure 2 is an elevational view of one side of the handle.

Figure 3 is a bottom plan view.

The conventional portions of a cutlery blade shown in dotted lines in Figures 1, 2 and 3 are only for the purpose of illustration.

I claim:

The ornamental design for a handle for cutlery or the like, substantially as shown and described.
